STOCKING

Percy S. Curry, Bland Courthouse, Va., assignor
to Bland Hosiery Mills, Inc., Bland Courthouse,
Va., a corporation of Virginia

Application May 23, 1952, Serial No. 19,860

Term of patent 14 years

(Cl. D47—7)

To all whom it may concern:

Be it known that I, Percy S. Curry, a citizen of the United States and a resident of Bland Courthouse, Bland County, and State of Virginia, have invented a new, original, and ornamental Design for a Stocking, of which the following is a specification, reference being had to the accompanying drawings, forming part thereof.

I claim:

The ornamental design for a stocking, substantially as shown and described.

PERCY S. CURRY.
